FIG. 7

INVENTOR.
Hattiam Bosworth
BY *Julian A. Polack*
ATTORNEY

UNITED STATES PATENT OFFICE

HALLIAM BOSWORTH, OF DOUGLAS MANOR, NEW YORK

SUMMER GARMENT

Application filed December 23, 1929. Serial No. 415,923.

This invention relates to new and useful improvements in a garment and has more particular reference to garments to be worn by men or women in the summer. It is intended that these garments take the place of the outer coat, vest and outer shirt.

It is proposed to design these garments so that in wearing them a person is completely dressed. At the same time great comfort is obtained in that they are all that is worn over the underwear. Preferably these garments should be made of madras, linen, duck, pongee, silk or other light material that is washable. When wearing these garments in hot weather, one can be completely comfortable because only two light thicknesses of goods are being worn. The garments may be designed in either one or two pieces.

The invention particularly proposes a shirt portion cut and finished for simulating a jacket or other exterior wearing apparel so as to eliminate the necessity of wearing a conventional vest and jacket. The invention also proposes trouser portions cut and finished to go with said shirt portion and eliminate the necessity of standard trousers.

It is a further object to provide a union garment consisting of a combination of said shirt and trouser portions. It is also proposed to produce blousing and pleated effects, and a means for maintaining each of the pleats.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is an elevational view of a shirt portion constructed according to this invention.

Fig. 2 is a perspective view of a trouser portion constructed according to this invention.

Fig. 3 is an elevational view of a union garment consisting of shirt and trouser portions.

Fig. 4 is a rear elevational view of Fig. 3.

Fig. 5 is a view similar to Fig. 3 but showing another design of the garment.

Fig. 6 is another view similar to Fig. 3 but showing another design.

55

Fig. 7 is a fragmentary pictorial view of the garment shown in Fig. 6 applied upon a person.

Fig. 8 is a fragmentary enlarged detailed view of pleats used in the various garments described and provided with the means for maintaining their form.

Fig. 9 is a horizontal sectional view taken on the line 9—9 of Fig. 8.

60

In Fig. 1, a coat 10 has been shown preferably made of some washable material such as pongee-silk, light duck, linen, heavy madras or any other desired material and cut and formed in any desirable fashion. As shown on the drawing, the sleeves 11 are of elbow length, but they may be made shorter or may be full length. The ends 12 of the sleeves are set up with a band for trimming. In the event that full length sleeves are used, they may be finished at the ends like those of a tailored suit or shirt.

75

The neck 13 of the coats is full and cut low to avoid uncomfortable thickness and warmth of the regular collar in present use. The collar 14 may be either attached or unattached. If unattached, a collar of the same material as the coat or a white collar may be used. A flowing tie of the artist variety may be worn which goes very neatly with the coat, or if so desired any other type may be used instead.

80

The garment is provided with pockets 16 of the type generally used in ordinary coats. Patch pockets are considered most practical for a washable garment. As the garment is not to be worn open the pocket indicated by reference numeral 16' near the right sleeve is a slit pocket in place of the inside pocket in an ordinary coat and is reached from the outside. A button 17 is used to close this pocket for preventing the losing of articles.

85

Since the material used will be thin, the pockets should be lined to strengthen them for the articles they will have to contain. The rest of the coat should have no lining. It should be made as light as possible so as to be

100

inexpensive both in manufacture and laundering.

Preferably it should be cut a little shorter than the prevailing style at any time, of a regular coat so that when the air turns a little cooler than usual, the regular coat may be slipped on over it and conceal it in the same way that it does to a shirt. This coat is worn over the underwear requiring no shirt such as is worn at present. It may be worn with trousers to match or may be worn with the regular trousers in place of the present day coat. On the trousers either a belt or suspenders may be used since they are covered up and not seen.

In Fig. 2, trousers 18 have been shown to go with the coat just described. They are shown provided with bottom cuffs 19 though this is not intended as a limitation since they may be plain or of the present day golf trouser type. Along the top the trousers are provided with loops 20 for receiving a belt 21. As before stated either a belt or suspenders may be worn as the coat falls outside the trousers. Buttons should be sewn upon the trousers along the top edge for use in the event that suspenders are desired. The belt 21 should be very thin material so as to be cool.

In Figs. 3 and 4, a one piece garment 22 has been illustrated. It is a combination of the coat and trousers all in one piece. As shown the design is such that the legs have the golf trouser finish 23. The sleeves 24 may be either long or short. The garment is drawn in at the waist by a waist band 25 and the lines of the waist band are formed with pleats 26 running vertically as shown on the diagram. The pleats are also formed in the back as may be seen from an inspection of Fig. 4.

Pockets may be arranged as desired. These pockets may be at the sides where they are usually found in regular trousers. Other parts of the garment not specifically called to attention are the same as in the garments previously described. The back of the garment is shown formed with a flap 27 which can be buttoned to the waist band at 28. The loops for the belt should be sewn upon the top of the flap so that when the belt is run thru them, the buttons are concealed.

The goods is extended partly around the back as indicated by numerals 29 to mask the openings at the sides between the waist band and the lower part of the flap. One corner 55 of the flap is shown turned up for illustrating the loops 20. It is intended that this type or any other type of flap be used on all garments of one piece.

In Fig. 5, a one piece garment 30 has been shown very similar to the garment shown in Fig. 3. It distinguishes in that the trousers 31 are of conventional design in lieu of the golf trouser type shown in the previous figure. Further, the sleeves 32 are of full length. This garment is also provided with

the pleats 26 which are formed in both shirt and trouser portions.

In Fig. 6, another design of union garment has been shown. This garment is of exceptionally loose cut so that it may be bloused as indicated by numeral 34 in Fig. 7. It is provided at the waist with loops 35 for the reception of a belt. As shown, it has golf type legs.

The means for holding the pleats 26 in form consists of a pair of spaced strings 36 attached at one of their ends upon the material of the garment on opposite sides of the pleat. One pair of strings are provided for each pleat. A stiff member 37 with curved ends 38 is tied down by the strings so as to limit expansion or contraction of the material forming the pleat. The length of the stiff member 37 is materially shorter than the distance between the ends of the pair of strings which are attached to the material in spaced relations and end to end alignment so that when the strings are tied over this member, the material of the garment is loose and may be formed into the pleat.

A hook 39 is supported by an elastic string 40 attached upon one end of the stiff member 37 and catches upon one of the bends of the pleat. Another hook 41 catches upon the other end of the pleat and is supported by an elastic member 42 passing thru an aperture 43 in the material, and at its other end is attached upon the stiff member 37. Obviously the pleat is firmly held in form. It is intended that the belt of the garment pass over the means for holding the pleats in form so that they are not visible.

If desired, the pleats may be opened by untying the strings 36, removing the hooks 39 and 41 from the material of the pleat and then removing the stiff member 37 together with the elastic strings and hooks. The strings 36 remain permanently attached upon the material of the pleat.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A union garment, comprising a shirt portion, a trouser portion connected with the shirt portion, said shirt and trouser portions being provided with vertical pleats, means engaging over the pleats for holding the material of the garment loose at portions so that the loose material may be formed into said pleats, comprising strings attached to the said material, a stiff member tied down by said strings, and resilient means connected be-

tween said stiff member and loose material for holding the pleat formation.

2. A union garment, comprising a shirt portion, a trouser portion connected with the shirt portion, said shirt and trouser portions being provided with vertical pleats, means for each pleat and engaging over said pleat for holding the material of the garment loose so that the loose material may be folded into the said pleats comprising a pair of strings in end to end alignment attached at their ends to the material in spaced relation, a stiff member with curved ends tied down by said pair of strings, and resilient means for each pleat connected between said stiff member and the folds for holding the pleat formation.

3. A garment, comprising a shirt portion, a trouser portion with a drop seat, said garment being provided with vertical pleats, means for each pleat and engaging over said pleat for holding the material of the garment loose so that the loose material may be folded into the said pleats comprising a pair of strings in end to end alignment attached at their ends to the material in spaced relation, a stiff member with curved ends tied down by said pair of strings, and resilient means for each pleat connected between said stiff member and the folds for holding the pleat formation, comprising a hook engaging one of the folds of the pleat and attached upon an elastic attached on one end of said stiff member, and another hook engaging the other fold of the pleat and attached upon an elastic passing through an aperture in the material and secured upon the other end of the stiff member.

In testimony whereof I have affixed my signature.

40 HALLIAM BOSWORTH.
